His ATTORNEY.

UNITED STATES PATENT OFFICE.

JAMES P. GOGGIN, OF CENTRAL FALLS, RHODE ISLAND, ASSIGNOR TO GENERAL ELECTRIC COMPANY, A CORPORATION OF NEW YORK.

BLOWPIPE-CLEANING DEVICE.

1,234,010.

Specification of Letters Patent.

Patented July 17, 1917.

Application filed October 21, 1914. Serial No. 867,926.

To all whom it may concern:

Be it known that I, JAMES P. GOGGIN, a citizen of the United States, residing at Central Falls, county of Providence, State 5 of Rhode Island, have invented certain new and useful Improvements in Blowpipe-Cleaning Devices, of which the following is a specification.

My invention relates to apparatus for removing the residue of glass or the moil which is left on a blow-pipe after the removal of the blown article therefrom. My invention affords a very efficient and conveniently operable apparatus which may be used in connection with the blowing of glass articles in any known manner. The advantages of my invention are particularly apparent in connection with the use of glass blowing machines in which a removable blow-pipe is employed, as its use dispenses with the necessity of an operator who would otherwise be required to accomplish its function.

An object of my invention is to produce a device of the character above referred to which will remove the glass residue or moil effectively and rapidly, and, moreover, which is of such construction that the blow-pipe may be very conveniently brought into and out of operative relation thereto. Further advantages and features of my invention will appear from the detailed description of a species thereof which follows, and from the accompanying drawing.

In the drawing, Figure 1 is a side and Fig. 2 is a front elevation of one form of my invention. Fig. 3 is a view in perspective showing the moil removing blades and the position of the blow-pipe with reference thereto. Fig. 4 is an enlarged side elevation of the said blades and their mounting, and Fig. 5 is an enlarged front elevation of the same.

Referring to the drawing, 10 is a shaft journaled in a frame comprising the standards 11 and the cross-pieces 12. The said shaft is rotated by any suitable means, such as the motor 13, by means of the pulley 14 and belt 15. Mounted on the shaft 10 and, preferably, so that they are adjustable thereon, are the blades 16. These are preferably angularly disposed with reference to each other. The said blades are suitably spaced from each other so that the blow-pipe may be inserted therebetween. The

adjustment may be secured by means of the screws 17, which pass through the hubs 18, to which the blades are attached. The said screws engage the shaft 10.

Although the above described apparatus 60 is operable as described, it is preferable to have a means for supporting the blowpipe during the moil removing operation in proper relation to the above described blades. As shown in the drawing, such a 65 support is afforded by the forks 19, the relative height of which is such that the blowpipe, when placed in engagement therewith, is given the proper upward inclination so that the end thereof is struck by the ends 70 of the blades. The said forks are supported in the bracket 20, which may be suitably secured to the standards 11.

It is desirable, also, to provide means for catching the pieces of glass which are detached from the blow-pipe by the blades. As shown, this consists of a box 21 disposed back of the above described parts, and having an opening 22, and extending somewhat above, below and on each side of the 80 blades and adjacent parts.

During the operation of the above described apparatus the blades 16 are rapidly rotated. The moil carrying blow-pipe is laid upon the guide forks 19 so that the end 85 thereof projects between the rotating blades. The ends of the said blades will then strike the glass and remove the same. During this operation the blow-pipe may be rotated, which will facilitate the operation. The 90 detached glass will be knocked into the box 21 through the opening 22 therein.

It will be apparent that the above described apparatus may be connected up with a blowing machine so that it will not 95 require a separate motor. It will be apparent also that various changes may be made in the above described apparatus without departing from the scope of my invention, which is stated in the appended 100 claims.

What I claim as new and desire to secure by Letters Patent of the United States, is:—

1. In a moil removing apparatus, the 105 combination of a rotatable shaft and radially extending blades mounted thereon in parallel planes, the blades in one set being angularly disposed with reference to the blades of the other set and the two sets be- 110

ing spaced a suitable distance to receive the end of a blow-pipe therebetween and adapted to operate simultaneously on opposite sides of the blow pipe.

- 5 2. In a moil removing apparatus, the combination of a rotatable shaft, radially extending blades adjustably mounted thereon in parallel planes, the blades in one set being angularly disposed with reference to the 10 blades of the other set and the two sets being adapted to be suitably spaced apart so as to receive the end of a blow-pipe therebetween and operate simultaneously on opposite sides thereof.
- 15 3. In a moil removing apparatus, the combination of a rotatable shaft and radially extending blades mounted thereon in parallel planes, the two sets of blades being spaced apart so as to receive the end of a 20 blow-pipe therebetween and adapted to operate simultaneously on opposite sides of the blow pipe, and means for supporting a blow-pipe with its end in operative position with reference to the ends of said blades.
- 25 4. In a moil removing apparatus, the combination of a rotatable shaft and radially extending blades mounted thereon in parallel planes, the two sets of blades being suitably spaced apart to receive the end of a blow- 30 pipe therebetween and adapted to operate

simultaneously on opposite sides of the blow pipe, and a receptacle having an opening therein opposite to the said blades and adapted to catch the detached glass.

5. In a moil removing apparatus the combination of a horizontally disposed rotatable shaft, and two sets of shearing blades mounted on said shaft and extending radially therefrom in parallel planes, said sets of blades being suitably spaced to receive 35 the end of a blow-pipe extending transversely of the said shaft and adapted to operate simultaneously on opposite sides of a blow pipe when the shaft is rotated.

6. A moil removing apparatus comprising 45 a rotatable shaft and two sets of adjustable shearing blades mounted on said shaft and extending radially therefrom in parallel planes, said sets of plates being suitably spaced to receive the end of the blow pipe 50 and adapted to operate simultaneously on opposite sides thereof when the shaft is rotated.

In witness whereof, I have hereunto set my hand this 17 day of Oct., 1914.

JAMES P. GOGGIN.
